COAT HANGER

William Backer, Schenectady, N. Y., assignor to
 Swan Cleaners & Furriers, Schenectady, N. Y.,
 a firm composed of Kalman Backer, William
 Backer, and Simon Backer

Application June 10, 1935, Serial No. 25,703

1 Claim. (Cl. 223—88)

This invention relates to garment hangers or as they are usually simply called "coat hangers", and particularly the kind that are made out of wire.

5 These wire hangers are light and inexpensive and widely used for these advantages. As heretofore constructed however, they have been objectionable because the sharp ends of the wire exposed at the tip of the supporting hook and at 10 the twist about the shank of the hook have a tendency to catch and tear the garments with which the hangers are used.

The objects of this invention are to provide a wire hanger which will be free of these objections, which will be stronger and better constructed than previous hangers of this type and which with such advantages, will still be practically as light and inexpensive.

These and other desirable objects are attained 20 by the novel features of construction hereinafter disclosed and broadly claimed.

The drawing accompanying and forming part 25 of the following specification illustrates certain practical embodiments of the invention, but it will be clear from an understanding of the invention that certain changes and modifications may be made all within the true spirit and broad scope of the claims.

Fig. 1 in the drawing is a view in elevation of 30 one of the new coat hangers.

Fig. 2 is a broken partly perspective view of the novel hook and shank construction of the hanger embodying the concealed and protected joint of the wire ends.

35 Fig. 3 is a view like Fig. 1, illustrating a modification in which the wire ends are abutted and joined beneath a shoulder portion of the hanger.

As will be clear in the several views, the hanger 40 consists of a single length of wire which is doubled on itself at 5, to form a smoothly rounded tip and parallel side parts 6, 7. The latter in this doubled side-by-side relation are bent to form the supporting hook 8 and then twisted together at 9, into a shank or neck formation.

45 In the first illustrated form of the invention, Figs. 1 and 2, one end of the wire terminates in this twisted shank portion approximately at 10, and the other end of the wire terminates at 11, in opposition to and in substantial abutment with 50 the first end.

This novel relation is accomplished by twisting the second considered end portion of the wire together with the first portion at 12, as a continuation or extension of the twisted neck 9.

Thus as indicated more clearly in the enlarged

view, Fig. 2, the twisted shank of the hook is made up of upper and lower coiled sections of the wire, 9 and 12, with the ends of the same meeting at 10, 11, substantially mid-length of the coils.

In completing this structure, the opposed wire 5 ends may be rolled down into close tightly coiled abutting relation and, if desired, may be welded or otherwise suitably secured in actual abutting engagement. With a sufficient number of wraps however, the wire ends need not be affixed to 10 each other or special care taken to set them in actual abutment, so long as they are close enough for one end to serve to cover and shield the opposite end.

In the second form of the invention illustrated 15 in Fig. 3, the doubled portions of the wire are continued on past the twisted together shank portion 9 and the ends at 10a and 11a, brought together in abutting engagement beneath one of the shoulder curves 13, 14, of the hanger and 20 there welded or similarly secured in such relation as indicated at 15.

In both forms of the invention, the ends of the wire are concealed and shielded so as to leave no exposed sharp edges and the hook is formed with 25 a smooth rounded tip. This construction requires but little more material than that needed for ordinary hangers and furthermore, locates this slight extra material in the hook and shank portion of the hanger where it is desirable as reinforcement for these portions. Any slight crevice or gap that may be left between the substantially abutting ends 10, 11, in the twisted shank of the hook may ordinarily be filled with the enamel, 30 paint or other coating usually applied to these articles, thus entirely concealing the joint between the wire ends.

What is claimed is:

A coat hanger consisting of a single length of wire having the ends of the same abutted and 40 welded together in a continuous endless loop of wire, portions of said endless loop, including said joined ends, being doubled in parallelism and the doubled end part of such portions being bent into a supporting hook, the parallel portions of the 45 base of said hook and including said joined ends being twisted in the form of a hook shank and said joined ends being located between opposing convolutions of said twisted shank and the remainder of said endless loop extending oppositely 50 from said twisted shank in spaced shoulder forming portions connected across the bottom of the hanger by an integral spreader portion.
